SPRING ASSEMBLY

Louis J. Zerbee, Bellefontaine, Ohio

Application July 6, 1937, Serial No. 152,122

17 Claims. (Cl. 155—179)

This invention relates to a resilient structure and more particularly to a resilient structure adapted for use as a cushion for seats and back rests.

5 Various types of cushions for seats and back rests in chairs and the like have been used. In other chairs no cushions have been used. When cushions are used either the cushioning qualities are inferior or the cost of the cushions is rather 10 high.

An object of the present invention is to provide a cushion that is easily made, cheap and at the same time durable, comfortable and satisfactory.

Another object of this invention is to provide a 15 cushion made from articulated resilient members.

Another object of this invention is to produce a cushion from a foraminous member.

Another object of this invention is to produce a 20 cushion from a metallic screen woven from resilient material.

Another object of this invention is to produce a cushion from a foraminous member wherein the resiliency in the bonds between the holes is utilized for cushioning purposes.

25 Another object of this invention is to provide a stranded screen member as a cushion, wherein the strands do not extend continuously through the body of the cushioning member.

Another object of this invention is to provide a 30 cushion for the seat of a chair from a screen wherein the natural curvature of the screen is utilized to provide sufficient rigidity.

Another object of this invention is to provide a cushion for the back rest of a seat where the back 35 rest has been curved in opposition to the natural curvature of the screen to thereby produce a cushion having the proper resiliency.

Another object of this invention is to provide a pair of cushions, one of which is made from a 40 screen flexed in the direction of the natural curvature thereof, in the other of which is flexed in opposition to the natural curvature.

Another object of this invention is to produce a 45 cushioning device made from a screen woven from spring wire.

Another object of this invention is to provide a screen having strands at least some of which are made of spring wire.

Other objects and advantages reside in the construction of parts, the combination thereof and the mode of operation, as will become more apparent from the following description.

Fig. 1 is a perspective view of the preferred 50 embodiment.

Fig. 2 is a cross sectional view taken substantially on the line 2—2 of Fig. 1.

Fig. 3 is a cross sectional view of the seat of a chair taken substantially on the line 3—3 of Fig. 2. Fig. 3 is drawn to a larger scale than Fig. 2.

Figs. 4—9 inclusive shows steps of manufacture of the cushioning device.

Fig. 10 is a cross sectional view of another modification of a seat structure.

Fig. 11 is a perspective view of another modification. 5

Fig. 12 is a cross sectional view taken substantially on the line 12—12 of Fig. 11.

Fig. 13 discloses another modification of a 10 screen.

Fig. 14 discloses another modification of a screen.

It has been found that a screen made from high carbon steel, or other suitable resilient material such as brass, will, if provided with the proper 15 curvature, produce a very satisfactory cushion. Furthermore, it has been found that the screen made from high carbon steel as it is reeled from the roll has a natural curvature caused from being rolled, which curvature is utilized to provide 20 the proper resiliency. If the screen is formed into a cushion by bending the screen in opposition to the natural curvature, the resulting structure has less resiliency than if the screen is curved in the direction of its natural curvature. By 25 utilizing a cushion made from a screen formed in the direction of the natural curvature, a comparatively rigid seat portion may be made having the proper resiliency for carrying the weight of the body. The same material may be used for a 30 back rest, which is preferably made by flexing the material in opposition to the natural curvature.

In the preferred embodiment disclosed in Fig. 1, the reference character 10 indicates a pair of resilient legs merging into a rearwardly projecting 35 base portion 12 resting on the floor and the rearwardly projecting arm portion 14 suitably attached to the back rest 16.

As may best be seen by referring to Fig. 2, the seat portion includes a pair of frame members 20 40 and 22 extending continuously around the outer periphery of the seat. An articulated foraminous screen 24 made from suitable resilient material, such as high carbon steel, is clamped between members 20 and 22, which are held in fixed spaced 45 relation by suitable rivets 26. The screen 24 forming the cushion of the seat is preferably made from high carbon steel wires woven into a screen having eight mesh to the inch. The seat portion 24 is preferably formed by exerting a 50 pressure upon the screen having a natural curvature like that indicated by the reference character 23 seen in Fig. 4.

The natural curvature of the blank 23 is caused by the screen usually being handled in a roll 55 when shipped from the mill to the factory. The blank 23 is placed in the forming die where a portion indicated by the bracket 30 is subjected to a force exceeding the elastic limit over this area, so as to form the blank into a cross sectional area 60

like that shown in Fig. 5. Then, by flexing the screen shown in Fig. 5 within the elastic limit, it is formed into the seat portion 24 having the cross sectional area shown in Figs. 3, 6 and other figures. This portion, it will be noted, has been formed by bending the blank in the direction of the natural curvature.

The back portion 16 is made from a blank screen 32 shown in Fig. 7. This blank form is placed in a suitable forming device where an area 38 is subjected to a pressure exceeding the elastic limit so as to cause a curvature of the screen throughout this area, so that the blank 32 assumes the shape shown in Fig. 8. This blank shown in Fig. 8 is then formed into the shape shown in Fig. 9, where it is held in position by suitable clamping bands 20 and 22.

By producing a seat utilizing the natural curvature of the material which provides flexibility to the back rest formed in opposition to the natural curvature, the proper resiliency for the seat portion and for the back rest may be obtained from the same type of material. The same results could, of course, be obtained by utilizing a flat blank having the proper resiliency. It would then probably be necessary to use one type of material for the seat portion and another type of material for the back portion. The seat and back rest could also be made from different types of materials having a natural curvature, both bent in the direction of the natural curvature, or both bent in opposition to the natural curvature, providing materials are selected that will give the proper results by so doing.

It is not necessary to use a screen having a natural curvature. Flat pieces of screen either woven or apertured, as hereinafter more fully described, may be used, providing screens of the proper resiliency are selected.

The forward portion of the seat is attached to the upright portion of the legs 10. The sides of the back rest may be attached to the rear end of the arm rests 14 by means of a suitable bracket 34. An angle bracket or angle iron 36 holds the rear portion of the seat and the bottom of the back rest in proper relation to each other.

In the modification disclosed in Fig. 10, the screen portion 40 has the upper part contoured much the same as that shown in Fig. 3; but in the modification disclosed in Fig. 10 the screen overlies or extends over the outside of the supporting member 42. The screen has a reentrant portion 44, clamped between member 42 and a retaining member 46. These members may be held in position by rivets 48, by suitable bolts or screws, or by welding. The back portion of the chair may be made in a manner similar to that disclosed in Fig. 10.

The modification disclosed in Fig. 12 is a cross sectional figure similar to the cross sectional Figure 3 of my Patent No. 2,046,715 dated July 7, 1936, which has been modified so as to incorporate the foraminous cushion, as will be described more fully later. The seat and back portion in this modification is made integral from a sheet metal member 50, provided with a marginal bead 52, extending continuously along the sides of the seat, along the sides of the back 70 and over the top of the back, like that disclosed in my patent. The central portion of the seat has been cut away. The margin of the opening is reversely folded upon itself, forming the reentrant flange 54. The bight of the reentrant flanges 54 engages and clamps the margin 56

of the screen cushion 58 contoured so as to have the proper resiliency. The cushion 58 has portions near the margin formed by a force exceeding the elastic limit of the material, so as to have the proper contour to produce the desired result.

In the modification disclosed in Fig. 13, a foraminous screen member 60 has been shown, provided with a plurality of perforations 62 bounded by bonds or strands 64. The sheet metal used in producing member 60 is made from a suitable resilient material, as for example, high carbon steel or the like. The bonds 64 do not run continuously throughout the strip, but are interrupted so as to bound only two squares 15 on each side or less, as the case may be. These bonds are easily flexed whenever a pressure is exerted upon the screen in a direction normal thereto. Due to the resilience of the material, it will spring back into the original position immediately upon the release of the pressure. This foraminous screen may be used as a cushion material much the same as the woven screen described above, or it may be used as a flat seat, as the material will flex without being originally 25 curved.

In the modification disclosed in Fig. 14 a foraminous screen 70 has been shown, wherein the apertures 72 are arcuate and circumferentially arranged. The apertures are arranged in concentric rows wherein the apertures in each row are staggered with respect to the apertures in the adjacent rows. This provides bonds or strands 74 between the apertures, which bonds do not extend in a straight line across the screen. 35 These bonds upon being subjected to a pressure normal to the plane of the screen are flexed or bent; but spring back into the original position immediately upon the release of the force. This foraminous member may be formed into an arcuate formation or may be used flat, much the same as the modification disclosed in Fig. 13.

Although the cushion has been shown in connection with a chair, especially a chair adapted for porch or outdoor use, the invention is equally as applicable to cushions used in other types of seats such as rocking chairs, office chairs, automobile seats, airplane seats and pews. Furthermore, the use of the cushions is not limited to the use in seats. These cushions may be used in upholstering furniture, they may be used instead of the conventional bed springs or they may be used for other cushioning devices, as for example, cushion on billiard tables or the like. Furthermore, the resiliency of the screen may be used as a substitute for other types of springs.

The metallic screen described thus far has been made from spring material. Instead of being made exclusively from spring material, some of the strands may be made of spring wire, others 60 of soft wire or fibrous material. Likewise, the wires may be woven into fabric so that the finished product will simulate fabric, but reinforced by the resilient wires, so as to have the proper cushioning effects. In such a structure the wires 65 may be alternated with the woof and the warp of the fabric. Instead of being alternated, the wires may be grouped, running parallel to the woof or parallel to the warp, or both. For some purposes the woof may be made from resilient 70 steel wire and the warp from soft wire having very little resiliency, or vice versa. This depends entirely upon the demands of the finished material.

Although the preferred modification of the de- 75

vice has been described, it will be understood that within the purview of this invention various changes may be made in the form, details, proportion and arrangement of parts which generally stated consist in a device capable of carrying out the objects set forth, in the novel parts, combination of parts and mode of operation, as disclosed and defined in the appended claims.

Having thus described my invention, I claim:

1. A cushioning device for a chair or the like including supporting means and a unitary metallic screen of resilient material formed into arcuate shape having a greater curvature near the peripheral margins than the curvature of the central portion, said greater curvature being arranged in spaced relation from said supporting means and means engaging the margins of the screen throughout its entire periphery for supporting the same and preventing movement of the margins 20 of the screen, but permitting a yielding movement of the screen inside the margins.

2. A cushioning device including a metallic screen woven from spring steel wire, said metallic screen being formed into arcuate formation 25 having a greater curvature near the margins than the curvature of the central portion and means for limiting the free movement of the margins, said greater curvature being arranged in spaced relation from said means.

3. A cushioning device including a metallic screen having arcuate portions, said screen being woven from high carbon steel wire and means for restricting the movement of a portion of the screen in spaced relation from the arcuate portions, but permitting free movement of other portions thereof.

4. A cushioning device including an arcuate metallic screen woven from transversely disposed resilient wire and means for restricting the free 40 movement of a portion of the wire, but permitting yielding movement of other portions thereof.

5. A cushioning device including an arcuate metallic screen woven from drawn spring wire and means for restraining the free movement of 45 a portion of the screen, permitting yielding movement of other portions thereof.

6. A resilient supporting device including an arcuate screen woven from drawn spring wire and supporting means therefor, said supporting means 50 restraining the movement of one portion of the screen in one direction, said supporting means permitting other portions of the screen to yield in response to a force applied thereto.

7. A body supporting cushioning device including a unitary screen woven from spring wire having a peripheral curvature in spaced relation from the margins, said peripheral curvature being curved through a substantial arc, and means arranged in spaced relation from the peripheral curvature for restraining the wires of the screen 55 so as to hold it in tension.

8. A unitary cushioning device for a body supporting portion of a chair or the like, said cushioning device including an arcuate screen member, and supporting means for supporting the margins of the screen in tension, the curvature of the screen being greater near the margins adjacent the support but in spaced relation therefrom than in the center of the screen, the curvature of the screen when released from the support 60 being different from the curvature thereof when mounted upon the support.

9. A resilient device including a surrounding

support and a foraminous metallic screen mounted in said support, said screen having zones of a lesser radius of curvature than the balance of the screen, said zones being spaced from the support and initially formed by being subjected to 5 a force exceeding the elastic limit, said support restraining the movement of a portion of the screen and exerting a tension upon the screen so as to hold it flexed within the elastic limit.

10. A cushioning device for a seat of a chair or the like including an arcuate fabricated member woven from transversely disposed elongated spring members, and means marginally engaging said fabricated member, the curvature of which is greater near the margins thereof but in spaced 15 relation from said supporting means than the curvature of the central portion thereof.

11. A cushioning device for a chair or the like including a spring formed from a sheet of metallic screen woven from drawn high carbon 20 steel wire, said screen being convexed, and supporting means engaging the margins of the screen to fixedly hold the same.

12. A body cushioning device for use in chairs or the like consisting of a single flat piece of screen 25 woven from spring wire at least a part of the outside edges being formed into arcuate formation having a greater curvature than the central portion of the piece of screen so as to set up bow-like stresses in said central portion, and supporting means engaging at least a portion of the margins 30 of the screen to hold the same in position.

13. A cushioning device for a seat of a chair or the like including an arcuate fabricated screen woven from transversely disposed spring wires, 35 the curvature of said screen increasing towards the margin, and means engaging said screen for supporting the same.

14. A cushioning device for a chair or the like including a spring formed from a sheet of metallic screen woven from drawn high carbon steel wire, said screen being convexed, and supporting means engaging at least a portion of the margins 40 of the screen to hold the same in position.

15. A cushioning device for a chair or the like including a spring formed from a sheet of curved metallic screen woven from drawn high carbon steel, and supporting means engaging at least a portion of the margins of the screen to hold the same in position, the curvature of the screen 45 when released from the support being different from the curvature thereof when mounted thereon.

16. A cushioning device having supporting means including a reentrant flange forming a bight, said cushioning device including a metallic screen woven from spring wire, the main body having a curvature, which curvature merges into a flange along the margin projecting into the bight of the supporting means and clamped 55 therein so as to support a portion of the screen in fixed relation with respect to said supporting means.

17. A cushioning device having a fixed support including clamping means, said cushioning device including a resilient metallic arcuate screen the curvature of which terminates in a reentrant flange, said flange being clamped in said clamping means so as to rigidly support the flange but permit yielding movement of other portions of the 60 screen.

LOUIS J. ZERBEE.
